CHARGING DEVICE FOR CHARGING LIQUID
COKING MATERIAL INTO COKE OVENSHerbert Gruber, Essen, Germany, assignor, by
mesne assignments, to Koppers Company, Pitts-
burgh, Pa., a corporation of DelawareApplication December 19, 1938, Serial No. 246,591
In Germany December 22, 1937

9 Claims. (Cl. 202—149)

The present invention relates to contrivances for charging liquid coking materials, such as pitch or the like, into chamber or retort ovens for the production of gas and coke and more particularly into ovens with high narrow chambers or retorts.

Hitherto the liquid material to be coked was charged gradually into the coke oven through nozzle-like pipes, arranged in the oven roof, so that within a period of say 2½ to 3 hours the oven chamber was slowly filled and at any given period only a small quantity of the liquid came into contact with the wall faces.

It was found that by such a charging of the oven chambers with liquid material, destructions will be met with on the wall faces within a certain period. I have found from experience that these difficulties result from the fact that part of the jets of the liquid material, entering the chamber from above, is deflected in such a manner that the liquid on entering always touches the same zones of the wall faces. The liquid, for instance coal tar pitch, is suitably preheated to a temperature of about 310° C. before being filled into the coking chamber. This temperature is above the so-called first conversion point of the silica material used for the construction of the coking chambers. A cooling down of the front faces of the bricks down to about 310° C. is, therefore, not dangerous so that a gradual charging of the coking material in the manner suggested above will not affect the brick material.

If, however, the liquid material on entering is touching repeatedly the same zones of the wall faces having a temperature of about 300° C. or less, than a stronger and also a more intensive cooling down to 300° C., i. e. below the first conversion point of silica, is rendered possible. Such a cooling down and subsequent reheating has a dangerous effect upon the silica material since the temperature of the silica material varies repeatedly just about the first conversion point of the silica and consequently the silica brick will deteriorate on account of the change in volume which takes place on passing the said conversion point.

Now, the main object of my present invention is to provide a contrivance for charging liquid coking materials into coke oven chambers which eliminates such disadvantageous cooling down of the walls of the coking chamber or retort.

According to the invention, this improvement is obtained by feeding the liquid material to be treated into the oven chamber through one or

several pipes extending approximately down to the oven sole, said pipe having a longitudinal slot extending from the lower end of said feeding pipe up to the desired level of the charge. The pipe is preferably introduced into the oven chamber at one end of the coking chamber and the longitudinal slot directs the liquid on entering towards the other end of the chamber. The liquid to be treated flows slowly through said pipe or pipes into the chamber onto the top of the material already charged in, and no liquid material can be thrown against the walls of the oven chamber, and the charging takes place gradually in accordance with the time of filling.

The provision for inserting the charging pipe, designed according to the invention, only at one end of the oven chamber still offers other essential advantages, which are likewise the object of my present invention, which in the main consists of providing every oven chamber with a single charging point which may easily be connected with known circulating pipes, arranged along the oven battery above the charging holes of the individual chambers, and through which the liquid is kept in continuous circulation. These circulating pipes arranged on the oven roof are, according to the invention, provided with an outlet for each charging hole of the battery, each outlet controlled by a cock which is designed in such a manner that, in every position of the cock plug, which is preferably connected with the outlet pipe it is provided for, and which plug is actuated by means of this outlet pipe to open and closed position, the hot liquid may circulate through the pipe system.

According to the invention, the outlet pipes are connected with the neck of the plugs and are also bent-off angularly in such a manner that they project, while in charging position, into the mouth of the corresponding oven charging pipe, which on its top is provided with a funnel. On turning these outlet pipes so that the pipe end is within the range of the funnel of the oven charging pipe, the cock plug is turned simultaneously in such a manner that the liquid may flow from the circulating pipe into the oven chamber. Such a flow of liquid is interrupted by closing the plug again on turning back the said outlet pipes.

In accordance with the invention, the charging of the coking chambers may also be effected by means of a charging device travelling over the oven roof. This charging device is provided either with lifting means for withdrawing the charging pipe introduced into the oven, or such

a lifting contrivance may further be arranged for separate travel beside the charging device on the oven roof.

With the above and other objects and features of my present invention in view, I will now describe a preferred embodiment of my invention on the lines of the accompanying drawings, in which:

Fig. 1 is a longitudinal section through an oven chamber built according to the present invention;

Fig. 2 is a side view of a part of an oven battery in accordance with the invention;

Fig. 3 is a longitudinal section through a shut-off cock used in connection with the apparatus according to Fig. 2;

Fig. 4 shows another mode of carrying out the invention with a stationary circulating pipe arranged on the oven battery;

Fig. 5 is a longitudinal section through a shut-off cock adopted for the contrivance of Fig. 4;

Fig. 6 illustrates a longitudinal section of the shut-off cock according to Fig. 5;

Fig. 7 shows the connection of the charging cock with the oven charging pipe of the contrivance according to Fig. 4;

Fig. 8 shows a charging device for travelling over the oven roof combined together with a manipulating device for lifting the charging pipe;

Figs. 9 and 10 finally illustrate a longitudinal section through the end of an oven chamber, and a front view of the oven battery, showing a separate travelling charging device, and lifting device each for the oven charging pipe.

The coke oven illustrated in Fig. 1 comprises the narrow horizontal coking oven chamber 1 which is closed gas-tightly by door closure means 2 and its two oppositely disposed longitudinal walls which are heated by the heating flues arranged in the manner well known for the ordinary coal coking ovens. For simplicity's sake the heating flues are not shown on the drawings. The oven roof 3 is provided with an opening 4 which is closed by a lid 5 during the coking process. The opening 4 serves for the introduction of the charging pipe 6 into the oven chamber. The charging pipe 6 reaches almost down to the oven sole 7 and its lowermost position is secured by a collar 8 surrounding the pipe, said collar 8 fitting tightly against the mouth of the opening 4 in the oven roof. The charging pipe 6 has a longitudinal slot 9 arranged to extend throughout the height of the charge. Said slot is directed towards the other end of the oven chamber. The charging pipe 6 with its upper end 10 projects from the oven roof and is fitted with a traverse 11 by means of which it may be drawn out of the oven chamber. The upper end 10 of the charging pipe is constructed like a funnel.

A circulating charging pipe 13 fitted with shut-off cocks 14 is arranged firmly on the brackets 12 on the oven roof. These shut-off cocks 14 are situated beside the charging holes 4 in the oven roof of the coking chambers of the battery. The oven charging pipe 6 is inserted into the oven chamber by a lifting device 16a travelling over a rail 15a arranged at a suitable height above the oven roof and is extracted from the oven chamber likewise by the device 16.

The design of the shut-off cocks 14 is shown more fully in Fig. 3. As may be seen therefrom, the cock comprises a casing 14 in which is rotatably arranged an inner conical casing 16. The inner casing 16 is engaged by a usual hollow conical plug 15, the latter being provided

with an axially hollow projection 22. The inner casing 16 may be secured to the casing 14 by means of the flanges 17.

Between the inner casing 16 and the cock casing 14 is left a free space 25 which serves as a by-pass for the liquid circulating through the pipe. The casing 16 is likewise provided with an opening 18 lying in the range of the pipe 23. The opening 18 coincides with the opening 19 arranged in the plug 15. The plug 15 is held in the casing usually by means of a flange 20 and tightened by a stuffing box 21. The plug 15 and its neck 22 are hollow so that the liquid material may flow through the opening of the neck 22 when the cock is in opened position as shown on the drawings. A part of the liquid material entering through the pipe 23 may flow always through the by-pass 25 into the pipe 26. The hot material is, therefore, in continuous circulation through the pipes 23, 26 and it is prevented from refrigerating and solidifying in the circulation system.

An angularly bent pipe 27 is firmly screwed to the neck 22 of the plug cock 15 so that on turning said pipe 27, the plug cock 15 is reversed. The arrangement is such that in case the pipe 27 is in lifted position as may be seen from Fig. 2 the opening 19 of the plug cock 15 is out of the range of the opening 18 of the inner casing 16 and consequently the flow of the liquid through the hollow plug and the pipe 27 is interrupted. While in charging position of the pipe 27 as shown in Fig. 2, in connection with the middle cock marked 14a, the openings 18 and 19 of the plug cock and of the inner casing coincide so that the liquid material may freely discharge from the circulating pipe into the charging branch. The charging branch 27 is secured in the charging position as well as in the closing position by means of a spring 28 fastened to the bracket 12. The liquid is delivered through the pipe 13 and passes around the casing of all the shut-off cocks 14 partly or completely corresponding to their position, through the above mentioned by-passes 25 of the cock casings. Finally it flows through the pipe 29 back again into the tank where it is heated to the desired temperature.

In Fig. 4, the circulation pipes are marked 32 and 33, the former serving as forerun, the latter as backrun. The pipes 32, 33 are arranged laterally above the charging openings 30, 31 which are provided in the oven roof near one end of the coking chamber. Cocks 34, 35 are arranged in the pipes 32 and 33 at those points lying between two adjacent charging openings. Each of the plugs of both the cocks 34 and 35 are connected with a branch 36, 39 similar to the cock shown in Fig. 3. A special charging cock 38 is connected with the other end of the pipe branches 36, 37 in pairs. Said cock 38 is arranged in such a manner that it may be moved just above the upper end of two adjacent charging pipes 10, the latter being introduced into the chamber to be charged and brought in charging position.

The design of the charging cock 38 as well as of the straight-way cock 34, 35 is fully shown in Figs. 5-7. The charging cock 38 is designed similar to the cock illustrated in Fig. 3 and comprises a casing 41 in which is arranged rotatably the conical cock plug 43 having a downward extension in the form of a branch 42. The casing 41 is fitted with lateral connecting parts 44, 45 to which are connected the angularly bent pipes 36, 37 in a rotatable manner by means of stuffing boxes 46. The two parts 44, 45 of the

casing 41 are interconnected through a by-pass 48 leading around the cock plug. A continuous flow of liquid may take place through this by-pass 48. In charging position, the connecting part 45 is in connection with the inner space 41 of the cock plug through an opening 49 so that the liquid material arriving through the pipe 36 may discharge through the hollow extension 42 of the cock plug and the oven charging pipe 10 connected therewith.

The charging cock may be reversed in such a manner that the extension 42 fitted with a thread 50 after the charging cock is moved within the range of the funnel-like head 51 of the oven charging pipe 10, is connected with the threaded head 51. Preferably the charging funnel 51 is turned in a stuffing-box-like guide 53 attached to the charging pipes 10 by means of the lever 52 provided on the charging funnel 51 until the threaded part of the pipe 10 engages the thread arranged at the lower end of the cock extension 42. On a further turning of said funnel, the opening 49 of the cock plug is brought into the range of the connection 45 provided in the casing 41 so that the liquid material may pass to the charging pipe 10. Reversely, the charging cock is closed by rotating the cock plug and disengaging the thread of its extension. In each case, the opening position and the closing position is determined by a stop screw 54' provided above the cock plug 43 in the cock casing 41.

The throttle cocks 34, 35 as may be seen from Figs. 5 and 6 can likewise be designed in such a manner that the liquid material may always flow through the casing of these cocks. The plug 54 of the throttle cocks, the neck 55 of which is connected the respective pipe 36, 37, consists of two projections 57 facing each other and fitting to the round inner wall of the casing for the plug. On the mouth of the branches 58 in the middle space of the casing is arranged a partition closing said mouth at one side. It is thus possible to bring the projections 57 as shown on the drawings in the dot and dash lines 57a, 45 by turning the cock plug 54 into the fully opened position, into such a place that the liquid may freely circulate through the cock casing. The circulation of the liquid through the forerun and backrun by-passes 32, 33 may be reduced in that the plug 54 is turned into the position shown in full lines on the drawings. According to Fig. 6 the branch 58 on the right side is closed by one of the projections 57 while the other branch 58 is open towards the casing.

In case the right hand branch 58 (Fig. 6) is fully or partly closed by the one of the projections 57, the left hand branch 58 is opened and the liquid may flow through said branch into the cock casing, thence through the opening provided for in the cock neck 55.

The charging contrivance illustrated in Fig. 8 mainly comprises a car 60 which travels above the charging openings by means of the travelling wheels 61 over a machine track 63 arranged on the oven battery 62. The car 60 is fitted on the top with a frame 64 in which is arranged a lifting device 65 serving to extract the oven charging pipe 10 from and lower it into the cooking chambers of the battery. An essentially rectangular supporting frame 66 is arranged on the car 60. This supporting frame 66 has beams 67 on the bottom and a vertical guide 68 fitted thereto. A supporting plate 69 is fixed to the upper part of the charging pipe 10, said supporting plate 75 having a projection engaging the guide 68 and

resting upon the beams 67 when the pipe 10 is lowered into its charging position and thus supports the charging pipe 10, suspending it in the oven chamber.

At both sides of the travelling rails 63 are the circulation pipes 71 supported in pipe hooks 72. To the circulation pipes 71 on each travelling rail there are arranged angularly bent pipes 73 revolving in stuffing-box-like members 74. The lower ends of pipes 73 are likewise angularly bent and also rotatably connected with pipes 75 by means of a stuffing-box-like casing 74. The pipe 75 with its upper end angularly bent is rotatably supported in the stuffing box casings 76 which are movably fastened to levers 77. The levers 77 are fixed to a shaft 78a arranged on the frame 66. The pipes 78 are firmly connected with the stuffing box casings 76 which lead to a charging cock 79. This cock 79 is fitted below with an outlet pipe 80 which is screwed into the funnel-like head of the charging pipe 10 in a similar manner to that already described in connection with the arrangement shown in Fig. 7. The charging cock 79 is similar to the charging cock shown in Fig. 7 and provided with a by-pass for a continuous circulation of the liquid.

The pipe system 73, 75, 78 is therefore guided on both sides of the machine track so that when travelling the car 60 over the track 63 the whole pipe system follows the movement of the car. The pipes 73, 75 are, therefore, of such a length that the charging openings 5 of the whole battery or of a part thereof may be connected to the charging pipe 10.

If the charging contrivance has reached the correct charging position above the oven chamber, first of all the car is blocked by means of an interlocking device 83 arranged on the supporting frame 66, said interlocking device engaging in suitable locking cams 84 provided therefor on the machine track 63. The charging pipe 10 is then introduced into the oven chamber by lowering the lifting device 65 and secured to the frame 66 in the described manner. The hand lever 81 arranged on the shaft 85 which is supported in the car and which has a lever 82 parallel to the levers 77, which lever 82 is movably connected with the charging cock 79, is then operated to connect the charging cock 79 to the charging pipe 10, through the parallel rods and levers 77, 82 and the outlet branches 80 of the charging cock 79, in the described way. Whether the hot liquid tar pitch is charged into the oven chamber or not, the hot liquid will circulate through all parts of the charging system. If for instance the liquid arrives through the pipe line 71 arranged on the left side of the machine track, it flows through the pipes 73, 75, 78, which are connected with the pipe line 71 in a movable manner, and then enters the return pipe line 71 arranged on the right hand side of the track-way.

Since the charging process takes about $2\frac{1}{2}$ to 3 hours it may be advantageous to provide separate cars for the charging device for and for the device manipulating the charging pipes, instead of having said two contrivances arranged on a common car. This is of special advantage if a single charging device has to fill so many oven chambers successively that the period between the completion of the charging procedure of one chamber and the beginning of the charging procedure of the next following chamber is very short so that little time will be left for removing the charging pipe from one chamber 75

and for suspending it into the next one. In this case at least two charging pipes 10 will be used.

As shown in Figs. 9 and 10 the charging device 86 is movably suspended from a travelling rail 87 which is fastened to a supporting construction provided on the buckstays 88 of the oven battery. The charging device 86, travelling laterally of the charging openings arranged 10 on the oven roof 3, is guided below in a track 90 and thus prevented from side movements. The delivery and return pipes 91 are fastened to the supporting constructions 89 to which are connected, similar to the contrivance shown in 15 Fig. 8, the movably guided pipes 93 leading to the charging cock 92. A special lifting device 94 is arranged for travel on a track provided on the oven roof and facing the charging device 86. The lifting device 94 is supported at the 20 top by means of a roller 97 travelling on the rail 96 arranged on the brackets of the supporting construction 89. For removing the charging pipe 10 out of the oven chamber by means of hand gearing 98, a double lever 99 fitted with recesses 25 is turned around in such a manner that the recesses engage in suitable projections of the charging pipe 10 so that after a previous removal of the charging cock 92 out of the range of the charging pipe to be extracted, the charging 30 pipe can be taken out of the oven.

The charging device described above can also be advantageously used in those cases where as usual hitherto, several charging pipes are provided for each coking chamber. In this event 35 the horizontal part of the pipe 100b of the contrivance is elongated to such an extent that it reaches beyond all the charging openings arranged in the roof of the individual coking chambers. With this pipe 100b serving as a 40 distributor several charging pipes 10 are connected which by suitable lifting devices are introduced into the chamber and extracted therefrom. The charging pipes may in this case also be carried out in the described way.

45 The whole charging device together with the lifting device is suitably placed upon a car which travels over the rails of the coal charging lorry or over another rail track. It is then possible to charge the coking chambers of a coke oven battery alternatively with coal or a liquid coking material for instance pitch, as required.

I have now above described my present invention on the lines of a preferred embodiment thereof but my invention is not limited in all 55 its aspects to the mode of carrying it out as described and shown, since the invention may be variously embodied within the scope of the following claims.

I claim:

60 1. Apparatus for charging high narrow coke ovens, heated by two oppositely disposed longitudinal heating walls, with liquid coking material comprising feed and return pipes situated above the oven roof for circulation of heated liquid coking material; charging pipe for connection therewith and extending into the oven chamber through the oven roof, and in which said charging pipe is adapted to reach nearly down to the sole of the oven chamber from the 65 feed pipe during charging and has an outlet-means extending up from the lower end of the pipe to the height to which the oven is to be filled, said outlet-means being restricted so as to confine the liquid to flow in direction lengthwise of the heating walls of the oven chamber.

2. Apparatus for charging high narrow coke ovens, heated by two oppositely disposed longitudinal heating walls, with liquid coking material comprising feed and return pipes situated above the oven roof for circulation of heated liquid coking material; charging pipe for connection therewith and extending into the oven chamber through the oven roof, and in which said charging pipe is adapted to reach nearly down to the sole of the oven chamber from the 10 feed pipe during charging and has a slot extending up from the lower end of the pipe to the height to which the oven is to be filled, said slot being restricted so as to confine the liquid to flow in direction lengthwise of the heating 15 walls of the oven chamber.

3. Apparatus for charging high narrow coke ovens, heated by two oppositely disposed longitudinal heating walls, with liquid coking material comprising feed and return pipes situated above 20 the oven roof for circulation of heated liquid coking material; a charging pipe for connection therewith and extending into the oven chamber through the oven roof to the sole of the oven chamber, said circulating feed pipes being connected with the charging pipe through a reversing cock provided with a hollow cock plug and an outlet pipe line connected to the neck of the plug through which the liquid is introduced into the oven charging pipe, said plug being 25 opened and closed by the movement of the outlet pipe into and out of registration with the charging pipe, and said cock having a by-pass around the cock plug casing so that in any position of the cock plug the liquid may continue to 30 flow in circulation around the reversing cock to the circulating return pipe.

4. Apparatus for charging high narrow coke ovens, heated by two oppositely disposed longitudinal heating walls, with liquid coking material comprising feed and return pipes situated above the oven roof for circulation of heated liquid coking material; a charging pipe for connection therewith and extending into the oven chamber through the oven roof to the sole of the 45 oven chamber, said circulating feed pipes being connected with the charging pipe through a reversing cock provided with a hollow cock plug and an outlet pipe line connected to the neck of the plug through which the liquid is introduced into the oven charging pipe, said plug being opened and closed by the movement of the outlet pipe into and out of registration with the charging pipe, and said cock having a by-pass around the cock plug casing so that in any position of the cock plug the liquid may continue to 50 flow in circulation around the reversing cock to the circulating return pipe, said outlet pipe being rectangularly bent and fitting into a funnel-like head for the charging pipe during 60 the charging in such a manner that after turning the rectangularly bent pipe the charging turn may freely be removed, said rectangular pipe serving to open and close the plug simultaneously with its movement into and out of the 65 funnel.

5. Apparatus as claimed in claim 3 characterized by the provision of means whereby one reversing cock is connected for movement relative to the circulating pipes so as to serve each of 70 two adjacent oven chambers.

6. Apparatus as claimed in claim 3 characterized by the arrangement of a single reversing cock carried by means of the same operating device that is adapted for traveling above the 75

charging openings from oven to oven of a battery of the ovens and that serves for also effecting the introduction and extraction of the oven charging pipe into and out of the whole number 5 of ovens.

7. Apparatus as claimed in claim 3 and in which the neck of the charging cock is adapted for being screwed into the mouth of the oven charging pipe before the charging, by the turning 10 of the mouth of the charging pipe, and on further turning of the mouth of the outlet pipe when screw connected with the neck of the cock plug, the mouth guided on the oven charging pipe in stuffing boxes, opens the cock plug for 15 the delivery to the oven while a simultaneous flow of a partial quantity of the liquid continues

around the by-pass on through the circulation system.

8. Apparatus as claimed in claim 3 characterized by the introduction and the extraction of the oven charging pipes, on the one hand, and 5 the connection of the outlet pipe to the oven charging pipe for the charging, on the other hand, being effected by separate means.

9. Apparatus as claimed in claim 3, and in which the reversing cock is connected with the 10 circulation feed and return pipes by pipe sections each connected with another by a hinged joint for folding and unfolding action to reach various oven charging holes.

15

HERBERT GRUBER.
